UNITED STATES PATENT OFFICE.

RICHARD BERNHARD, OF ALLENTOWN, PENNSYLVANIA, ASSIGNOR TO THE TRAYLOR ENGINEERING & M'F'G CO., OF ALLENTOWN, PENNSYLVANIA, A CORPORATION OF DELAWARE.

GYRATORY CRUSHER.

1,336,015.

Specification of Letters Patent.

Patented Apr. 6, 1920.

Application filed May 2, 1919. Serial No. 294,254.

To all whom it may concern:

Be it known that I, RICHARD BERNHARD, a citizen of the United States, and resident of Allentown, Pennsylvania, have invented 5 certain new and useful Improvements in Gyratory Crushers, of which the following is a specification.

My present invention relates to improvements in gyratory crushers and aims to provide a construction in which the lower bearing for the shaft will be self-aligning and in which efficient means are provided for inclosing and lubricating the running parts, and further aims to provide improvements 15 designed to increase the efficiency and durability of the crusher and render certain parts more accessible.

With these and other objects in view the invention includes the novel features of construction and arrangement and combination of parts hereinafter described and defined by the appended claims.

An embodiment of my invention is illustrated in the accompanying drawings in 25 which:

Figure 1 is a sectional elevation, and

Fig. 2 is a similar sectional view showing a modified form.

Referring by reference characters to these 30 drawings the numeral 1 designates the shaft of the crusher, which carries the crushing cone 2 designed to coact with the concaves 3 in the usual manner. The shaft 1 may have its upper end suspended from and 35 journaled in the supporting member 4 in any suitable manner, such supporting connection being so arranged as to permit the shaft to be adjusted vertically to vary the discharge opening between the cone and concaves. The lower end of the shaft is 40 provided with a tapered portion or part 1^a terminating in a substantially cylindrical portion 1^b. Fitting over this part of the shaft is another or additional cylindric part which 45 may be in the shape of a sleeve 5 which has a cylindrical portion 5^b receiving the portion 1^b of the shaft and a flared upper end 5^a receiving the tapered portion 1^a of the shaft.

50 The sleeve projects beyond the lower end of the shaft and is closed at its lower end, forming an oil chamber 5^c, the extreme lower end being contracted and forming an annular external shoulder as indicated at 5^d. 55 Encircling the sleeve 5 is a rotatable eccen-

tric sleeve 6, which is provided with Babbitt metal 6^a in the usual or any desired manner. This eccentric is rotatably mounted in the bearing member 7 carried by the cylindrical member, or portion 8^a of the crusher frame 60 8. The eccentric 6 projects above the sleeve 5 and is flared at its upper end to correspond to the taper of the portion 1^a of the shaft, and said upper end projects into an annular recess formed in the lower part 65 of the crushing cone around the shaft a distance greater than the maximum amount of vertical adjustment of the shaft, this arrangement effectually preventing the entrance of any grit between the eccentric and 70 inner sleeve.

The upper end of the eccentric is rabbeted to form a portion 6^b concentric with the shaft and encircling this portion and resting upon the shoulder formed thereby, and 75 upon the upper end of bearing 7 is a floating grit excluding ring 9 for preventing foreign material from entering between the eccentric and the bearing member 7.

Fast to the lower end of the eccentric is 80 a bevel gear ring 10, which is driven by an intermeshing gear 11 fast on the end of drive shaft 12 journaled in suitable bearings 13 in the crusher frame, which shaft may have power imparted thereto in any 85 suitable manner.

The sleeve 5 is keyed to the shaft 1 in any suitable manner as by a key (not shown) passing through keyway or slot 5^c, and the portion 1^b of the shaft is preferably slightly 90 rounded toward either end, which permits of the sleeve automatically locating itself properly inside the eccentric to compensate for inequalities in machining and for wear on the babbitt.

95 I utilize the lower end of the sleeve to carry and effect the operation of the lubricating pump and to this end I detachably secure to said lower end a pump casing 14 in which are journaled the intermeshing 100 gears 15 and 16 constituting a gear pump. The shaft 16^a of gear 16 is located approximately in line with the axis of the shaft 1 and is projected through the bottom of the gear casing and is provided on its lower end with a gear 17 which meshes with a stationary gear ring or rack 18 carried by or formed integrally with the removable cover member 19. As the sleeve 5 and shaft 1 are held against rotary movement but are 110

carried bodily around in a circular path with a gyratory movement, due to the action of the eccentric it will be seen that gear 17 is caused to roll around on gear ring 5 or rack 18, thereby effecting the rotation of the pump gears.

The bottom of the gear casing is closed by a removable core plate 20 which has an annular oil chamber 20^a communicating 10 by flow and return ports *a* and *a'* respectively with the oil chamber 21 directly beneath the pump and with the gear casing.

As the oil level in the system is maintained at approximately the level of the bottom 15 of the teeth of gear ring 10 it will be seen that the gear pump is always submerged and no priming is necessary. The oil passes to the pump gear chamber through opening 21^a in the bottom thereof and is forced 20 out by the operation of the pump through opening 21^b into the space within the sleeve 5 beneath the end of the shaft, rising to the top of the sleeve, except for the portion 25 which passes through ports 5^x to the interior of the eccentric for lubricating the inner face of the latter. The oil which overflows at the top of the sleeve 5 passes by ports 6^x to the annular channel 7^x in the bearing 30 sleeve 7. This annular channel is formed in an enlarged portion of the bearing sleeve which overhangs and rests upon the upper 35 end of the frame part 8^a. The outer bearing of the eccentric receives its lubricant supply from this channel 7^x, the oil passing down therefrom between the outer surface of the eccentric and the bearing sleeve 7, one of these parts being preferably provided with oil grooves as indicated at *x*. The oil which descends through the grooves 40 to the bottom is thrown outward by centrifugal action over the gear 10, thereby keeping gears 10 and 11 thoroughly lubricated. From the channel 7^x the surplus oil passes through port *x* to pipe 21, by which 45 it is conveyed to an oil chamber 22, encircling the bearing of shaft 12 for lubricating the latter through ports 13^a. From this chamber the oil flows into the main gear 50 chamber and thence by ports *a'* before described to the core chamber 20^a. Any sediment in the oil will be collected and retained in chamber 20^a, the ports *a'* being elevated above the bottom thereof.

In order to make it possible to operate the crusher in either direction a double set of ports is provided, one set of which may be plugged up.

The pump is readily accessible from below 60 for cleaning and repair, it being only necessary for this purpose to remove the cap 19 when the bolts holding the pump casing to the bottom of the sleeve 5 may be withdrawn and the pump casing with gears 65 therein removed intact.

In some of the lighter forms of crushers I may omit the sleeve between the shaft and eccentric as shown in Fig. 2.

In this construction the pump casing 14^x is secured directly to the bottom of the 70 crusher shaft 1^y and a vertical oil passage *y* is provided in the crusher shaft having transverse passages *y'* leading to the eccentric bearing, and to the oil channel at the top, the construction remaining otherwise 75 substantially the same.

I prefer to provide a branch passage *y'* at the bottom forming with the main passage two ports leading to the pump casing, one or the other of which may be plugged up 80 according to direction of rotation desired.

Having thus described my invention what I claim is:

1. In a gyratory crusher the combination with the crusher frame and gyratory crusher 85 shaft carrying a crushing cone, of an eccentric journaled in the frame and encircling the shaft below said cone, said cone having an annular recess in its lower end adjacent the shaft into which the upper end of the eccentric extends.

2. In a gyratory crusher the combination with the crusher frame and crusher shaft carrying a crushing cone having an annular 95 recess, of a cylindrical bearing member carried by said frame, a bearing sleeve within said bearing member, an eccentric between said sleeve and shaft and projecting above the upper end of said sleeve and into an annular recess in the bottom of the crushing cone, said eccentric having a concentric portion above said sleeve, and a floating ring 100 encircling said concentric portion and resting on the upper end of said sleeve.

3. In a gyratory crusher the combination with the crusher frame and crusher shaft, and said frame carrying a cylindrical part encircling the shaft, of a bearing sleeve within said cylindrical part having an enlarged 110 upper end resting on the top of said cylindrical part, said enlarged end having an annular internal oil channel, an eccentric rotatably mounted between the shaft and bearing sleeve and projecting above the 115 latter and having an oil passage aligning with said channel, means for forcing oil up between the eccentric and shaft to said channel, and means for withdrawing oil from said channel.

4. In a gyratory crusher the combination with the crusher frame and crusher shaft, and said frame carrying a cylindrical part encircling the shaft of a bearing sleeve within said cylindrical part having an enlarged upper end resting on the top of said cylindrical part, said enlarged end having an annular internal oil channel, an eccentric 125 rotatably mounted between the shaft and bearing sleeve and projecting above the lat- 130

ter and having an oil passage alining with said channel, an oil pump beneath the lower end of said shaft and means whereby said pump is caused to move bodily in an eccentric path in unison with the eccentric movement of the shaft, for forcing oil upward to lubricate the eccentric and said channel.

5. In a gyratory crusher the combination, with the gyratory shaft having at its lower 10 end a cylindric part provided with oil passages and a rotatable eccentric encircling said cylindric part, of a lubricating device for the eccentric located beneath said cylindric part and comprising a pump casing 15 connected with said part, to be moved bodily through an eccentric path in unison therewith, pump piston means within said casing, and means coacting with a stationary part of the crusher for causing said eccentric 20 movement to actuate said piston means.

6. In a gyratory crusher the combination with the gyratory shaft and eccentric of lubricating devices for the eccentric including a pump casing beneath the shaft and 25 connected therewith to be moved in a gyratory path, a rotary pumping element in said casing having a shaft, projecting through the casing, a planetary gear on said projected shaft, and an annular stationary 30 rack with which said planetary gear engages.

7. In a gyratory crusher the combination with the shaft and eccentric of lubricating devices for the eccentric including a pump 35 casing beneath the shaft and connected therewith, pump gears journaled in said casing, one of said gears having a shaft projecting through the casing, a planetary gear on said projected portion, and an annular 40 stationary rack with which said gear engages.

8. In a gyratory crusher the combination with the shaft and eccentric having an operating gear at its lower end, of a gear casing 45 surrounding said gear provided with a bottom closure, a gear pump casing beneath the lower end of the shaft and removably connected therewith, pump gears in said casing, one of said gears having a shaft projected through the casing, a gear carried by 50 said projected shaft, said bottom closure having an opening in line with said pump casing, and a removable cover for said opening having an annular rack with which said gear meshes.

9. In a gyratory crusher the combination with the shaft and eccentric, operating gears for the eccentric, of a gear casing for said gearing, a removable bottom closure for said 55 casing having an annular oil collecting space and central chamber with ports in the walls thereof for conducting oil from said collecting space to said central chamber, and an oil pump located in said central chamber and operated from said shaft.

10. In a gyratory crusher the combination with the shaft and eccentric, operating gears for the eccentric, of a gear casing for said gearing, a removable bottom closure for said casing having an annular oil collecting 70 space and central chamber with ports in the walls thereof for conducting oil from said collecting space to said central chamber, and an oil pump located in said central chamber and operated from said shaft, said central 75 chamber having a removable cover for access to the pump.

11. In a gyratory crusher the combination with the crusher shaft and eccentric, of a sleeve interposed between the shaft and eccentric and keyed to the shaft and lubricating devices for the eccentric including a pump operated from said sleeve. 80

12. In a gyratory crusher the combination with a crusher shaft and eccentric, of a sleeve interposed between the shaft and eccentric and keyed to the shaft and lubricating devices for the eccentric including a gear pump having its casing detachably connected to the lower end of said sleeve. 90

13. In a gyratory crusher the combination with the eccentric and crusher shaft, of a sleeve interposed between the shaft and eccentric and depending below the end of the shaft and connected thereto and having a closed lower end forming an oil chamber, and lubricating devices for the eccentric including a pump connected to said closed lower end. 95

14. In a gyratory crusher the combination with the eccentric and crusher shaft, of a sleeve interposed between the shaft and eccentric and depending below the end of the shaft, and connected thereto and having a closed lower end forming an oil chamber, 100 and lubricating devices for the eccentric including a pump casing detachably secured to the outer face of said closed lower end, pump gears in said casing, an external gear connected to one of said pump gears, and 105 a stationary rack meshing with said external gear.

15. In a gyratory crusher the combination with the frame having a tubular bearing portion, the eccentric rotatably mounted therein, and the vertically adjustable shaft within the eccentric, of a sleeve interposed between the shaft and eccentric and having a slidable non-rotary connection with the eccentric, said sleeve having an annular external flange, and an annular internal flange on the eccentric engaging the annular flange 115 on the sleeve and supporting the latter. 120

16. In a gyratory crusher the combination with the frame having a tubular bearing portion, the eccentric rotatably mounted therein, and the vertically adjustable shaft within the eccentric, of a sleeve interposed between the shaft and eccentric and having a slidable non-rotary connection with the 125 130

eccentric, said sleeve having a reduced lower end forming an annular external flange, and said eccentric an internal annular flange engaging the flange on the sleeve and supporting the latter.

17. In a gyratory crusher the combination with the frame having a tubular bearing portion, the eccentric rotatably mounted thereon, and the vertically adjustable shaft 10 within the eccentric of a sleeve interposed between the shaft and eccentric and having a slideable non-rotary connection with the eccentric, means whereby said sleeve is supported by the eccentric, and lubricating 15 means for the eccentric including a pump operated from said sleeve.

18. In a gyratory crusher the combination with the frame having a tubular bearing portion, the eccentric rotatably mounted 20 thereon, and the vertically adjustable shaft within the eccentric, of a sleeve interposed between the shaft and eccentric and having a slideable non-rotary connection with the eccentric, and lubricating means for the eccentric including a pump supported by the lower end of said sleeve.

19. In a gyratory crusher the combination with the eccentric and shaft within the same, having a downwardly tapered portion 30 terminating in a substantially cylindrical portion, of a sleeve between the shaft and eccentric having a slideable non-rotary connection with said cylindrical portion, said sleeve having a flaring portion corresponding 35 to the taper of the shaft, and means whereby said sleeve is supported by the eccentric.

20. In a gyratory crusher the combina-

tion with the crusher frame and crusher shaft, and said frame carrying a cylindrical 40 part encircling the shaft, of a bearing sleeve within said cylindrical part having an enlarged upper end resting on the top of the cylindrical part, said enlarged end having an annular internal oil chamber, an eccentric 45 rotatably mounted between the shaft and bearing sleeve and projecting above the latter and having an oil passage alining with said channel, said channel serving to lubricate the outer bearing of the eccentric, 50 means for forcing oil up between the eccentric and shaft to said channel, and means for withdrawing surplus oil from said channel.

21. In a gyratory crusher the combination with the crusher frame and crusher shaft, and said frame carrying a cylindrical part encircling the shaft, of a bearing sleeve within said cylindrical part having an enlarged upper end resting on the top of said 60 cylindrical part, said enlarged end having an annular internal oil channel, an eccentric rotatably mounted between the shaft and bearing sleeve and projecting above the latter and having an oil passage alining with 65 said channel, means for forcing oil up between the eccentric and shaft to said channel, and an annular gear ring secured to said eccentric at its lower end and receiving oil from the outer bearing of the eccentric, 70 and means for withdrawing surplus oil from said channel.

In testimony whereof I affix my signature.

RICHARD BERNHARD.
